UNITED STATES PATENT OFFICE.

EUGENE C. RICHARD, OF FLINT, MICHIGAN.

CARBURETOR.

Application filed December 11, 1918. Serial No. 266,176.

To all whom it may concern:

Be it known that I, EUGENE C. RICHARD, a citizen of the United States, residing at Flint, county of Genesee, State of Michigan, have invented certain new and useful Improvements in Carburetors, of which the following is a specification.

This invention relates to improvements in carburetors.

10 My present improvements are designed by me for embodiment in carburetors such as shown in my co-pending application, Ser. No. 262,973, filed November 18, 1918, and I have, in the accompanying drawing, illustrated such an embodiment, as that is a form which I have found very practical. My present improvements are, however, capable of being embodied and desirable when embodied in other structures.

20 The main objects of this invention are: First, to provide an improved carburetor with means whereby the temperature of the air passing to the carburetor is effectively controlled with the adjustment of the 25 throttle.

Second, to provide an improved carburetor with an improved means for regulating the temperature of the air passing to and through the carburetor.

30 Further objects, and objects relating to structural details, will definitely appear from the detailed description to follow.

I accomplish the objects of my invention by the devices and means described in the 35 following specification. The invention is clearly defined and pointed out in the claims.

A structure which is a preferred embodiment of my invention is clearly illustrated in the accompanying drawing, forming a part of this specification, in which:

Fig. I is a front elevation of my improved carburetor.

Fig. II is a rear elevation of the structure 45 shown in Fig. I with the addition of a portion of the hot air supply connection.

Fig. III is an end view looking from the left of Fig. I.

Fig. IV is a detail front elevation with 50 the parts in the position occupied when the throttle valve is fully opened.

Fig. V. is a detail vertical section on a line corresponding to line 5—5 of Figs. III and VI.

55 Fig. VI is a detail horizontal section on

a line corresponding to line 6—6 of Figs. I, III and V.

Fig. VII is a detail vertical section through the air inlets on a line corresponding to line 7—7 of Figs. III and VI.

Fig. VIII is a transverse vertical section on a line corresponding to line 8—8 of Fig. VI.

In the drawing similar reference characters refer to similar parts throughout the several views, and the sectional views are taken looking in the direction of the little arrows at the ends of the section lines.

Referring to the drawing, the body of my improved carburetor consists of the chambered members 1 and 2, the chamber in the member 1 being an air supply chamber and that in the member 2 a mixing chamber. The member 2 is provided with a flange 3 for attachment to an engine with a delivery passage 4 controlled by the throttle 5. The member 1 has a nipple-like projection 6 at one side with which the air inlet passage 7 engages as shown in Fig. V.

The fuel reservoir 8 is disposed below the body member 1. The means for supplying and controlling the level of the fuel in the reservoir are not shown as they form no part of my present invention.

The air supply chamber communicates with the mixing chamber through the port 9 which is controlled by the suction actuated valve member 10. In the embodiment illustrated the fuel nozzle 11 delivers through the tubular valve member 12 to a carbureting chamber 13 within the member 10. This carbureting chamber 13 delivers to the mixing chamber above the port 9.

The member 10 is provided with a depending valve sleeve 14 telescoping over to the valve member 12 and a tapered primary air inlet valve 15 coacting with the valve member 12. The valve member 12 is actuated from the rock shaft 16 having an arm 17 thereon engaging the valve and an arm 18 adapted to engage the sleeve 14 when the member 12 is in its fully retracted position, thus holding the suction actuated member to its seat.

The rock shaft 16 projects through the casing and is provided with an actuated arm 19 and a stop arm 20. These parts and their operation are described in detail and claimed in my co-pending application. The air inlet passage 7 has rearwardly offset

hot and cold air inlet connections 21 and 22 respectively. These inlet connections are arranged in the same vertical plane.

In practice the inlet connection 21 is connected to a hot air conduit 23. These air inlet connections are controlled by the valves 24 and 25 provided with stems 26 and 27. These stems project at the rear to receive the arms 28 and 29 respectively, the arms 10 being connected by the link 30. These arms are preferably adjustably mounted on the stems to properly position the valves. They are arranged so that when the hot air valve is closed the cold air valve is 15 opened and vice versa. The hot air inlet valve is preferably cut away at 31 so that when closed it permits the passage of a limited quantity of hot air.

The valve stem 27 projects forwardly 20 through a bearing 32 in the passage member 7 to receive an arm 32. The stem 33 of the throttle valve 5 projects through the front of the carburetor body to receive an actuating arm 34 to which an actuating rod 25 35 is connected. The arms 32 and 34 are operatively connected by means of the link 36 which is pivoted to the arm 32 and slidably connected to the arm 34. A coiled spring 37 is arranged on this link, one end 30 of the spring engaging the arm 34 and the other a rest 38 on the link. A spring 39 is arranged on the link between the arm and the pin 40 at the outer end of the link. The spring 37 is of sufficient strength so that 25 when the throttle valve is opened the spring actuates the air valves which are arranged so that with the throttle closed the hot air valve is fully opened and the cold air valve closed, the hot air valve closing with the 30 opening of the throttle valve and the cold air valve opening and closing with the opening and closing of the throttle valve. The temperature of the air passing to the carburetor is thus effectively controlled, it being found that satisfactory results are produced when the temperature is raised upon the closing movement of the throttle, and vice versa.

To further control the temperature I provide a heating unit or element 42 within the mixing chamber adapted to be heated by means of the exhaust gases. This heating chamber has a heating medium connection 43 controlled by the valve 44. This valve is 50 controlled independently of the throttle and inlet valves so that it may be left full on in cold weather or closed in warm weather, and being capable of being adjusted independently of the air inlet and throttle substantially all conditions may be satisfactorily met.

My improved carburetor is highly efficient both in the matter of carburetion and in the economy of fuel.

60 I have illustrated and described my im-

provements in the form in which I have embodied the same. I have not attempted to illustrate or describe certain adaptations or modifications which may be desirable as I believe the disclosure made will enable those skilled in the art to which my invention relates to embody or adapt the same as conditions may render desirable.

Having thus described my invention, what I claim as new and desire to secure by Letters Patent, is:

1. In a carburetor, the combination of a throttle valve provided with a stem projecting at the front of the carburetor, an arm on said stem, an air supply passage at one side of the carburetor provided with rearwardly offset hot and cold air inlets disposed in substantially the same plane, valves for said hot and cold air inlets provided with rearwardly projecting stems, the stem 60 of one of said air inlet valves also projecting forwardly above the air supply passage which is provided with a bearing therefor, arms on the rearwardly projecting ends of said inlet valve stems, a link connecting said arms, said valves being disposed so that they are opened and closed alternately, an arm on the forwardly projecting stem, a link connected to such arm and slidably connected to said throttle valve arm, a spring disposed 65 on said link of such strength as to actuate said air inlet valves and permit further actuation of the throttle valve, a heating member disposed in the carburetor in the path of the mixture, a heating medium connection 100 for said heating member disposed above said air inlet passage, and a valve for said heating medium connection.

2. In a carburetor, the combination of a throttle valve provided with a stem projecting at the front of the carburetor, an arm on said stem, an air supply passage at one side of the carburetor provided with rearwardly offset hot and cold air inlets disposed in substantially the same plane, valves for 105 said hot and cold air inlets provided with rearwardly projecting stems, the stem of one of said air inlet valves also projecting forwardly above the air supply passage which is provided with a bearing therefor, arms on the rearwardly projecting ends of 110 said inlet valve stems, a link connecting said arms, said valves being disposed so that they are opened and closed alternately, the hot air inlet valve permitting the passage of a limited quantity of air when in its closed position, an arm on the forwardly projecting stem, a link connected to such arm and slidably connected to said throttle valve arm, and a spring disposed on said link of such strength as to actuate said air inlet valves and permit further actuation of the throttle 120 valve.

3. In a carburetor, the combination of a 125 throttle valve provided with a stem project-

- ing at the front of the carburetor, an arm on said stem, an air supply passage at one side of the carburetor provided with rearwardly projecting stems, the stem of one of 5 said air inlet valves also projecting forwardly above the air supply passage which is provided with a bearing therefor, arms adjustably mounted on the rearwardly projecting ends of said inlet valve stems, a link 10 connecting said arms, said valves being disposed so that they are opened and closed alternately, an arm adjustably mounted on the forwardly projecting stem, a link connected to such arm and slidably connected 15 to said throttle valve arm, and a spring disposed on said link at each side of said throttle valve arm of such strength as to actuate said air inlet valves and permit further actuation of the throttle valve.
- 20 4. In a carburetor, the combination of a throttle valve provided with a stem projecting at the front of the carburetor, an arm on said stem, an air supply passage at one side of the carburetor provided with rearwardly 25 offset hot and cold air inlets disposed in substantially the same plane, valves for said hot and cold air inlets provided with rearwardly projecting stems, the stem of one of said air inlet valves also projecting forwardly above the air supply passage which 30 is provided with a bearing therefor, arms on the rearwardly projecting ends of said inlet valve stems, a link connecting said arms, said valves being disposed so that they are 35 opened and closed alternately, the hot air inlet valve permitting the passage of a limited quantity of air when in its closed position,
- an arm on the forwardly projecting stem, a link connected to such arm and slidably connected to said throttle valve arm, a spring 40 disposed on said link of such strength as to actuate said air inlet valves and permit further actuation of the throttle valve, a heating member disposed in the carburetor in the path of the mixture, a heating medium connection for said heating member disposed above said air inlet passage, and a valve for 45 said heating medium connection.
5. In a carburetor, the combination of a throttle valve provided with a stem, an arm 50 on said stem, an air supply passage provided with hot and cold air inlets, valves for said hot and cold air inlets provided with projecting stems, arms on said inlet valve stems, a link connecting said arms, said 55 valves being disposed so that they are opened and closed alternately, a link connected to an arm on one of said inlet valve stems and slidably connected to said throttle valve arm, springs disposed on said link of such 60 strength as to actuate said air inlet valves and permit further actuation of the throttle valve, a heating member disposed in the carburetor in the path of the mixture, a heating medium connection for said heating member, and a valve for said heating medium 65 connection.

In witness whereof, I have hereunto set my hand and seal in the presence of two witnesses.
